UNITED STATES PATENT OFFICE.

FORTUNATO NEVEUX, OF RIVOLI, ITALY, ASSIGNOR TO O. M. I. M. OFFICINA MECANICA INDUSTRIA MOGLIERIA, OF TURIN, ITALY, A COMPANY.

CIRCULAR-KNITTING FRAME.

Application filed March 9, 1923, Serial No. 624,003, and in Italy March 17, 1922.

Knitting frames heretofore used, with inclined loop wheels of the French type, i. e. wheels having their axes inclined relatively to a radial axis of the machine, were particularly suitable for knitting cotton goods, but not adapted for knitting woolen and silk goods. For the reason that the latter threads being of a much more resilient nature than cotton thread the loops need to be held by the movable sinkers in the rotatable sinker wheel or loop wheel (mailleuse) until said movable sinkers actually complete the stitch, as happens for instance in the usual knitting machines with radial loop wheels, i. e. of the German circular type. However, in knitting machines with inclined loop wheels the knocking over device could not be suitably located internally of the loop wheel in order to operate the movable sinkers as required by the elastic nature of woolen and silk threads.

The first object of this invention is to enable the knocking over cam or other device to knock over the stitch in the same instant in which the loop is being released by the movable sinker in the loop wheel. Such an object is realized according to this invention by suitably shaping the movable sinkers and applying a fixed presser in lieu of the usual rotating presser. The shape of the movable sinkers is therefore the main object of the present invention.

Furthermore, since the fixed presser, under which the needles pass and have their beards pressed, would not permit the knitting of twilled or ribbed work, as said presser would successively and indiscriminately press all the needle beards, the present invention has for a further object the provision of a sort of movable additional heel or tail-piece to be applied to a certain number of the movable sinkers in the loop wheel, as desired in connection with the work to be manufactured, that will serve as intermediate members between the fixed presser and needle beards, so that said presser will operate said tailpieces to press the corresponding needle beards.

Figure 1 shows the special sinker according to the present invention, Fig. 2 shows a sinker modified by the addition of the movable heel, Figs. 3 and 4 are respectively a side elevation and a sectional vertical view taken on line A—A Fig. 3 of said additional heel. Fig. 5 shows the machine and

the manner in which the invention is used thereon. Fig. 6 is a view of a portion of Fig. 5 on an enlarged scale showing the relative positions of the sinkers, the needles, the knocking-over devices and the stationary cam 20.

Referring first to Fig. 1, each of the sinkers is shaped as a blade 1 horizontally mounted in the loop wheel, provided with an upper notch 2 near one end, engaging a rotatable plate 3 on the loop wheel, said plate keeping the sinkers in position to oscillate about its periphery. The sinkers are arranged and kept in the position described about the plate 3 by means of a helical spring 4 bent to form a ring, while another helical spring 5 similarly arranged engages all of the movable sinkers near the middle transversal plane, so as to press them against the edge of another disc 3' in the loop wheel, said second disc being shown in Fig. 5 of the drawing.

In Fig. 5, 14 is a rotating drum carrying on its upper face a series of circumferentially arranged needles 15. The loop wheel 14 consisting of rotatable disks 3 and 3' and sinkers 1, is mounted upon a shaft 25, which in turn is rotatably supported by a stationary bracket 16 and is driven from the drum 14 by means of the rack 17 and gear 18. A fixed cam 19 is arranged to extend downwardly above the sinkers in their lower position and to force them down between the needles to form the loops. Since the loop wheel rotates on an axis which is inclined relatively to the radius of the drum 14 the thread will be drawn under the beards of the needles without the usual longitudinal movement of the sinkers. A second stationary cam or presser 20 is arranged to extend downwardly from the frame 16 and to press down the beards of the needles in the region of recess 7 of the sinkers. The usual knocking-over devices 21 are arranged to be operated by the fixed member 22 to knock over the stitches in the same instant as the loops are being released by the movable sinkers. The knocking-over devices are maintained in position on the drum by a helical spring 23.

The sinkers are hook-shaped at 6 at their opposite end, said hooks being turned outwardly as regards the loop wheel, and as the drawing shows the lowermost sinker in the wheel, the hook shown in the drawing turns 110

downward. The sinkers are acted upon at their forward ends above the hook shaped portion 6 by a cam 19, designed to force them into the spaces between adjacent needles, so as to form loops and displace them towards the needle beards where the newly formed loops will be landed by the loops of the fabric upon operation of the knocking over device 21.

- 10 Such a displacement is usually effected by means of a horizontal cam causing each sinker in the loop wheel to move endwise in its plane, say radially of the knitting machine or axially as regards the loop wheel; 15 this working however does materially hinder the speed of the machine.

The knitting machines of the type disclosed herein do not require any longitudinal displacements of sinkers, since the loop 20 wheel forms a rotatable unity, turning on an axis inclined as regards the knitting needles thus enabling the highest speeds to be attained. Sinkers are arranged on the loop wheel with their notches or indentations 25 engaging the edge of the plate 3, so that the lowermost sinker will be at any time radially disposed of the knitting machine, so as to be easily inserted between two adjacent needles. By this arrangement, in the knitting machine with inclined loop wheels, the advantage 30 is obtained that the sinkers automatically, due solely to the rotation of the loop-wheel, force the loops from their initial place on the shank of the needle toward the beard.

35 Referring now to Fig. 1, showing the particular shape of the sinker which is the principal object of this invention, this sinker is provided with the usual parts 1, 2, 3, 4, 5, 6 above referred to, and furthermore with a recess 7 in its forward portion, of suitable shape to leave open and salient the needle beards, and allowing the fixed presser to exert its pressure directly above the beards, 40 when plain knitting is to be manufactured.

If on the contrary ornamental fabric is to be knitted, certain of the sinkers 1 will be provided with heels or tail pieces 8 (see Figs. 2, 3 and 4), each having a pair of holes 50 9 and 10 and preferably grooved lengthwise at the underside as shown at 11 in Fig. 4. A pivot pin 12 fits in the hole 10, while a relatively small pin 13 extends into the hole 9, thus allowing the tail-piece to oscillate 55 freely between the positions indicated re-

spectively in solid and in dotted lines in Fig. 2. By thus providing the loop wheel with sinkers shaped as shown in Fig. 1 and certain others shaped as shown in Fig. 2, the needle beards are not indiscriminately 60 pressed down by the fixed presser and it is possible to make any desirable ornamental or fancy work. This will act selectively on needles to produce ornamental stitches as is well known in the knitting art. 65

The sinkers are arranged in the loop wheel at a distance apart from each other, so as to allow a slight clearance between their front portions for the needle beards, this space being sufficient also to permit the use of sinkers with tail-pieces, as shown in Fig. 2, each tail piece being in the same vertical plane as the needle beard to be pressed. The tail-pieces will thus take the pressure of the fixed presser and close the needle beard in 70 the well-known manner.

What I claim as my invention is:

1. In circular knitting machines of the French type having a loop wheel for sinking loops, with a knocking-over device and a fixed presser adjacent said loop wheel, sinkers constructed to permit the beard presser to directly contact with the needles, and other sinkers disposed at intervals provided with a recess near the forward ends thereof and provided with an oscillating tail-piece at one side, this tail-piece acting as an intermediate member between the fixed presser and certain of the needle beards. 85

2. In circular knitting machines of the French type having a loop wheel for sinking loops with a knocking-over device and a fixed presser adjacent said loop wheel, sinkers constructed to permit the beard presser to directly contact with the needles, and other sinkers disposed at intervals provided with a pair of laterally extending pins and an oscillating tail-piece having a hole fitting one of the pins on the sinker and another hole loosely surrounding the other pin to allow the tail-piece to oscillate freely around the first-mentioned pin, the tail-pieces acting as intermediate members between the fixed presser and certain of the needle beards. 95 100 105

In witness whereof, I have hereunto signed my name in the presence of two subscribing witnesses.

FORTUNATO NEVEUX.

CERTIFICATE OF CORRECTION.

Patent No. 1,674,217.

Granted June 19, 1928, to

FORTUNATO NEVEUX.

It is hereby certified that the name of the assignee in the above numbered patent, was erroneously written and printed as "O. M. I. M. Officina Meccanica Industria Moglieria", whereas said name should have been written and printed as "O. M. I. M. Officina Meccanica Industria Maglieria", as shown by the records of assignments in this office; and that the said Letters Patent should be read with this correction therein that the same may conform to the record of the case in the Patent Office.

Signed and sealed this 28th day of August, A. D. 1928.

(Seal)

M. J. Moore,
Acting Commissioner of Patents.
